LEAD-HEADED NAIL

Raymond E. Camp and John J. Strysik, Joliet,
Ill., assignors to The American Steel and Wire
Company of New Jersey, a corporation of New
Jersey

Application June 17, 1935, Serial No. 27,071

5 Claims. (Cl. 85—28)

This invention relates to lead-headed nails which broadly consist of steel wire nails providing integral heads to which lead is applied so as to enclose the same.

5 One of the objects is to improve such nails so as to eliminate slipping or loosening of the lead respecting their steel heads. Other objects may be inferred.

Referring to the accompanying drawings:

10 Figure 1 shows the side of a nail which illustrates the present invention and as it appears before its head is enclosed with lead.

Figure 2 shows the top of this nail.

15 Figure 3 shows the nail after its head is enclosed with lead, the head and lead part being sectioned.

Figure 4 shows the same as Figure 3 except that it is not sectioned.

20 Figure 5 shows the side of the head of another nail which also illustrates the invention.

Figure 6 shows the top of the last named nail.

Figure 7 shows the side of a modified form of the nail shown by Figures 1 through 3.

Figure 8 shows the top of this modified nail.

25 Figure 9 shows the side of the head of still another nail which illustrates the invention.

Figure 10 is a bottom view of this nail.

More particularly, the nails are steel wire nails and each includes a shank 1 having a sharpened driving point 2, and a head 3 providing a plurality of spaced protuberances 4 on its top surface. Specifically, there are four protuberances which are arranged close to the circumference of the head and are equidistantly spaced from each other. They are of substantial height and provide flat inclined anchoring surfaces for the lead. Hence they may be either rectangular or base as in the case of the protuberances 4 shown by Figures 1, 2 and 3, or may have triangular bases as in 30 the case of the protuberances 4^a shown by Figures 5 and 6. In all cases they are of sufficient height to function as anchors for preventing slippage or loosening of the lead which eventually encloses their heads. Preferably, they should be about as 35 high as the heads are thick.

40 In their final form the nails further include the lead 5 which encloses their heads. This is shown by Figures 3 and 4 in the case of the first mentioned nail but either nail will obviously appear externally as is shown by Figure 4. The lead may have any outside configuration providing such 45 does not interfere with its intended function and encloses the nail heads.

The modified nail shown by Figures 7 and 8 is much the same as that shown by Figures 1 through 3. It also is a steel wire nail which includes a shank 6 having a head 7 that provides a plurality of spaced protuberances 8 on its top surface. It differs in that these protuberances extend upwardly from projections 9 formed in the periphery of the head. This particular nail may prove superior respecting its ability to prevent slipping or loosening of the lead which eventually encloses its head. It is to be understood that this nail likewise has its head enclosed by lead as is illustrated by the dotted lines in Figure 7.

The nail shown by Figures 9 and 10 includes a shank 10 and a head 11 having protuberances 12 which are similar to those described in connection with the nail illustrated by Figures 1 through 3, excepting that they are formed on the bottom surface of the head. This change may prove advantageous in some instances.

20

We claim:

1. A nail including a shank having a head providing a plurality of spaced protuberances on its top surface, said head and said protuberances being enclosed by a relatively plastic substance. 25

2. A nail including a shank having a head providing a plurality of spaced protuberances on its top surface, said head and said protuberances being enclosed by a relatively plastic substance, and said protuberances being shaped to provide flat inclined anchoring surfaces for said plastic substance. 30

3. A nail including a shank having a head providing a plurality of spaced protuberances on its top surface, said head and said protuberances being enclosed by a relatively plastic substance, and said protuberances being shaped to provide inwardly facing anchoring surfaces for said plastic substance. 35

4. A nail including a shank having a head providing peripheral projections and protuberances extending at angles from said head and said projections, said head, said projections and said protuberances being enclosed by a plastic substance. 40

5. A nail including a shank having a head providing peripheral projections and protuberances extending at angles from the tops of said head and said projections, said head, said projections and said protuberances being enclosed by a plastic substance. 45 50

RAYMOND E. CAMP.
JOHN J. STRYSIK.
